DESIGN FOR A MATCH COVER

Howard L. Fischer, St. Paul, Minn.

Application March 6, 1947, Serial No. 137,392

Term of patent 14 years

(Cl. D48—28)

To all whom it may concern:

Be it known that I, Howard L. Fischer, a citizen of the United States, residing in Saint Paul, county of Ramsey, and State of Minnesota, have invented a new, original, and ornamental Design for a Match Cover, for which the following is a specification, reference being had to the accompanying drawings, forming part thereof:

Dotted lines shown in the drawing are for illustrative purposes only.

I claim:

The ornamental design for a match cover, as shown and described.

HOWARD L. FISCHER.
